UNITED STATES PATENT OFFICE.

NOLLIE F. HENINGTON AND FANNIE D. HENINGTON, OF CRYSTAL SPRINGS,
MISSISSIPPI.

FRUIT-JAR SEALER.

1,179,308.

Specification of Letters Patent.

Patented Apr. 11, 1916.

Application filed January 28, 1916. Serial No. 74,940.

To all whom it may concern:

Be it known that we, NOLLIE F. HENINGTON and FANNIE D. HENINGTON, citizens of the United States, residing at Crystal Springs, in the county of Copiah and State of Mississippi, have invented certain new and useful Improvements in Fruit-Jar Sealers; and we do hereby declare the following to be a full, clear, and exact description of the invention, such as will enable others skilled in the art to which it appertains to make and use the same.

The invention relates to a fruit jar sealer for Mason jars.

It has been found by experience in the use of Mason jars that the engaging edge of the screw cap frequently gets bent out of shape so that it does not properly engage the rubber sealing ring and fails to make a perfect seal and frequently results in the spoiling of the contents of the jar.

The object of the present invention is to provide a simple, practical and efficient sealing device adapted after the screw top of a Mason jar has been applied to the same to engage the lower edge of the screw cap and straighten the same and cause the said edge to press properly into the rubber band and thereby produce a perfect sealing of the jar.

A further object of the invention is to provide a sealing device of this character capable of being readily applied to a jar and adapted to be adjusted to enable it to properly engage the lower edge of different screw caps.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawing Figure 1 is a vertical sectional view partly in elevation of a fruit jar sealer constructed in accordance with this invention, Fig. 2 is a horizontal sectional view on the line 2-2 of Fig. 1, Fig. 3 is a detail sectional view illustrating the manner of mounting the roller of the lever.

Like numerals of reference designate corresponding parts in the several figures of the drawing.

In the accompanying drawing in which is illustrated the preferred embodiment of the invention, the fruit jar sealer comprises in its construction a cap 1 constructed of sheet metal or other suitable material and consisting of a disk or plate provided with a depending annular flange 2 to fit around the upper portion of a screw top 3 of a Mason or similar fruit jar 4. The top is equipped with a centrally arranged vertically disposed pivot post 5 suitably secured at its lower end to the cap 1 and having a threaded upper portion 6 for engaging interior screw threads 7 of a knob or handle 8 which has a central vertical bore or opening extending upwardly from its lower end. The lower portion of the pivot post receives a rotary coupling block or member 10 having a central opening 11 for the said pivot post. The coupling block or member is provided at one side with spaced projecting ears 12 receiving a pivot 13 on which is mounted the inner end 14 of an operating lever 15 having an outer handle portion 16 and provided intermediate of its ends with a roller 17 for engaging the lower edge 18 of the fruit top 3 for spacing the said lower edge but any other suitable means may of course be employed for engaging and spacing the said edge. The roller 17 is mounted between spaced projecting ears or flanges 19 of a bearing bracket 20 secured to the lever at the under side thereof and set at an inclination, the roller being inclined and mounted on an inclined pivot 21. The lever is adjusted to arrange the roller in proper position for engaging the edge 18 by means of washers 22 arranged on the pivot post and adapted to be placed above and below the coupling member. The lever is swung around the pivot post and pressure is applied to the outer end of the lever while the knob or handle is held in one hand. This will cause the roller to engage the bottom edge 18 of the screw top and the said edge will thereby be straightened and forced into the rubber or other yieldable sealing ring and a tight joint or connection of a perfectly air tight character will thereby be obtained. This will enable screw caps to be used indefinitely and there

will be no necessity of discarding such caps because of the engaging bottom edge being bent out of shape.

What is claimed is:—

- 5 1. A fruit jar sealer including a cap adapted to be placed on a screw top and provided with a vertical pivot arranged centrally of the top, a knob or handle carried by the pivot, a rotary coupling member
- 10 mounted on the pivot, a lever pivoted at one end to the coupling member and arranged to swing upwardly and downwardly and also around the screw top and means carried by the lever and arranged to run on
- 15 the lower edge of the screw top.

2. A fruit jar sealer including a cap adapted to be placed on a screw top and

provided with a vertical pivot, a knob or handle carried by the pivot, a rotary coupling member mounted on the pivot, a lever pivoted at one end to the coupling member and provided intermediate of its ends with a roller set at an inclination and arranged to run on the lower edge of a screw top and washers mounted on the pivot and 20 25 adapted to be arranged above and below the coupling block for adjusting the lever.

In testimony whereof we affix our signatures in presence of two witnesses.

NOLLIE F. HENINGTON.
